UNITED STATES PATENT OFFICE

CLIFFORD HARRY ARMSTRONG, OF NORTH FINCHLEY, ENGLAND

FEED WATER REGULATOR

Application filed September 5, 1929. Serial No. 390,447.

This invention relates to feed water regulators for controlling the flow of water to steam boilers. The regulator is of the thermostat or expansion tube type. One of the objects of the invention is to provide a regulator which is very simple, compact and powerful, being so arranged as to eliminate stresses which tend to strain the apparatus and prevent positive action at all times. Another object of the invention is to provide for a large range in the elevation of the water in the boiler without passing beyond the limits of control of the regulator. Other objects of the invention will be apparent from a consideration of the accompanying drawing and the following description thereof.

Of the drawing, Fig. 1 is an elevation of a feed water regulator system which embodies the features of my invention; and Fig. 2 is an enlarged sectional elevation of the feed water valve of the system.

In this instance, I have shown the regulator associated with the boiler 10. The boiler has a water gage 11, and the regulator is designed to retain the water level elevation within the limits of the upper and lower petcocks 12 of the water gage, the average water level or the normal water level being substantially at the same elevation as the central petcock 13. These details, however, are not a necessary part of my invention. The thermostat itself comprises a V-shaped or U-shaped tube or, as is indicated, it may comprise the two tubes 15 and 16, suitably connected, by means of a coupling head 17, so that the tubes communicate with each other. The coupling 17, or the connected ends of the tubes if directly connected, are fixed in position. In this instance, the head is fixed to a stationary support 18. The upper end of the combined system communicates, by means of pipes 20, with the steam space of the boiler, and the lower end communicates, by means of pipes 21, with the water space of the boiler. As a consequence, the water in the thermostat stands always at substantially the same elevation as the water in the boiler.

As is well understood, with regulators of this nature, the thermostat is arranged so that, as it expands or contracts, owing to

variations in the water level, it operates the feed water valve so as to allow more or less water to pass into the boiler. In this instance, the connection between the thermostat and the feed water valve 22 comprises a system of levers so arranged that each branch of the thermostat, while operating its one lever, coacts with the other branch to operate a lever for controlling the valve.

The exact details of these levers is not essential but I prefer to have the upper branch associated with the bell crank lever 23 which is pivotally connected, by a link 24, with the common valve operating lever 25. The lever 25 is connected with the feed water valve by means of a link 26 and an arm 27, the arm being associated with the plunger 28 of the valve in a well known manner. A weight 30 at all times tends to open the valve when allowed to do so by the thermostat mechanism. The lower branch 16 of the thermostat is pivotally connected with the bell crank lever 31, which, by means of a link 32, is also pivotally connected with the lever 25 and, thus, coacts with the branch 15 in operating the lever 25 and also the valve plunger 28.

In operation, with the boiler carrying the normal or average load, and with the water level in the boiler about at the central petcock, the valve will be opened sufficiently to supply water substantially at the same rate as the output through the steam main and, in case of an increased load and corresponding lowering of the water level, the steam will pass into the upper end of the lower branch 16, and this branch will expand some and allow the long arm of the lever 25 to sink, thus opening further the valve and allowing more water to enter the boiler.

On the other hand, if the water rises above the normal elevation, it will pass into the upper branch 15, causing this branch to contract and this contraction will force the arm 27 upwardly and close further the valve, so as to bring the water level back to the desired elevation.

It will thus be seen that one branch or the other of the thermostat will vary the opening of the valve if the water level varies, as obviously the reverse process of that described

would follow the reversal of the water level change. And the limits of action of the thermostats will be the upper and lower ends of the two branches. So that, with two short tubes, instead of one long one of twice the length, assuming the inclination to be the same, the rigidity of the system is materially greater, as any bowing tendency of the short tubes is far less than that of a single long tube. Also, by increasing the lengths of the tubes, even without changing the inclination, the range of control will be increased accordingly.

Furthermore, the entire system is so arranged that there is no twisting tendency and no stress acting on any of the mechanism which tends to distort the mechanism. The stress on the branches of the thermostat is always that of straight tension and there is no twisting stress of any nature. So that, the slightest change in length of either branch of the thermostat produces its full effect on the movement of the valve. It will, of course, be understood that any positive loose play or slack is entirely taken up by the weight 30 and the weight of the operating mechanism.

The amount of the valve opening with reference to the water level elevation may be varied by adjusting the position of the coupling 17. This may be done by means of the bolt 34 which is threaded into the coupling and is held in position with reference to the support 18 by means of the lock nuts 35. By unscrewing the nuts somewhat, the thermostat will be shifted to the left, and this will allow the long arm of the lever 25 to sink and thus to open correspondingly the valve 22.

I claim as my invention:

1. A boiler system comprising a boiler, a feed water valve and a feed water regulator for controlling the flow of water to the boiler through said valve in accordance with the water level elevation in the boiler, said regulator comprising a V-shaped tube with its branches lying in the same vertical plane, communicating means connecting the outer ends of the branches with the boiler at two spaced points, and operative means connecting each of said ends with said valve, said means comprising a floating lever, each of said ends being operatively connected with one end of said lever, and the other end of the lever projecting towards the junction of said branches and being operatively connected with said valve, said lever being positioned between the branches of said tube, the inner end of said lever being mounted substantially over said feed water valve and the outer end being positioned in substantially the same plane as the ends of said tubes.

2. A feed water regulator comprising a V-shaped tube mounted with the branches of the tube lying in the same vertical plane, a

support for said tube, the outer ends of the branches of said tube being adapted to be operatively connected respectively with the steam space of the boiler and the water space of the boiler, the other ends of the branches being fixed to said support and communicating with each other, a floating lever positioned between the two branches and substantially in the same plane as the branches, lever means pivoted to said support connecting each of the outer ends with said floating lever at spaced points, and means connecting the inner end of said lever with said valve.

3. A feed water regulator for a boiler system, comprising a V-shaped tube and a T-shaped support therefor, the said tube being mounted in a vertical plane, with the cross member of the frame adjacent the outer ends of said tube, and with the apex of the tube fixed to the other end of the frame, levers pivoted to each end of the cross member and pivotally connected to the adjacent tube end, and a floating lever mounted between the branches of the tube with one end pivotally connected with each of said levers and with the other end operatively connected with the feed water valve of the boiler, the ends of the branches of the tube being in communication with the boiler at spaced points.

4. A feed water regulator as claimed in claim 3, in which all of said levers and connecting means lie in substantially the same plane as the tube branches.

5. A feed water regulator comprising a V-shaped tube, with the axes of the branches thereof lying in the same vertical plane, and the outer ends of the branches being adapted to communicate respectively with the steam space and the water space of the boiler, and operating means for connecting each of said ends with the feed water valve of the boiler, said means being arranged to produce at all times a tension on each of said tube branches.

In testimony whereof, I hereunto set my hand.

CLIFFORD HARRY ARMSTRONG.
